FRANCIS E. DAY, OF NEW YORK, N. Y., ASSIGNOR TO HIMSELF AND LYMAN H. DAY, OF SAME PLACE, ASSIGNEES TO JASON B. LOOMIS FOR ONE-HALF THEIR RIGHT.

Letters Patent No. 95,203, dated September 28, 1869.

IMPROVEMENT IN HOOP-SKIRT FASTENINGS.

The Schedule referred to in these Letters Patent and making part of the same.

To all whom it may concern:

Be it known that I, FRANCIS E. DAY, of the city, county, and State of New York, have invented a new and improved Mode of Securing the Hoops or Springs to the Tapes in the Manufacture of Hoop-Skirts; and I do hereby declare that the following is a full, clear, and exact description of the same, reference being had to the accompanying drawing, which forms part of this specification.

The general mode of securing the hoop to the tapes in the manufacture of hoop-skirts, is by means of a metallic fastening, (such as a clasp or eyelet,) which passes through the tape, and is turned down against or on the tape or hoop on the side opposite to that at which it enters. Such fastening is always liable to tear the fabric of the tape, and the points of the clasp are always liable to be bent outward and to tear the clothes of the lady, as well as to become loose, in which latter case the hoop becomes loosened from the tape, and liable to slide and get the skirt out of shape or to assume an unnatural position, injuring the "set" of the hoop-skirt; and further than this, the metallic fastenings are always visible on the outside of the skirt, and detract from the neat and attractive appearance of the hoop-skirt.

The object of my invention is to remedy all these prejudicial and objectionable features, and at the same time gain additional advantages.

My invention, therefore, consists in an improved method of securing the hoops or springs to the tapes in the manufacture of hoop-skirts, and it is effected by means of a metallic fastening which clasps the hoop on each side of the loop, casing, pocket, or "shirr" formed on the under side of the tape for the reception of the hoop or springs, whereby the hoop and tape are held securely in place, and without any metallic fastening passing through the same from the outside, or being visible on the exterior of the skirt; hence, a more durable, and more symmetrical, neat, and attractive article of ladies' wearing-apparel is produced, than the same article as at present constructed, where metallic clasps are used.

In the accompanying drawing—

Figure 1 is a front or outside view of a portion of one of the tapes of a hoop-skirt, with the hoops secured to it according to my invention.

Figure 2 is a back or rear-side view of the same.

Figure 3 is a vertical section taken on the plane of the line $z z$, fig. 2.

Figure 4 shows the tape with one edge turned down, to expose a portion of the clasp underneath.

Figure 5 is a perspective view of a clasp or fastening for securing the hoop to the tape according to my invention.

The tape A, illustrated in the drawing, is an article well known in the market, and used in the manufacture of hoop-skirts. It is woven with what are termed "shirrs," or loops, or pockets, $a a$, (see figs. 2 and 3,) on one side, (the side which is to be nearest the wearer of the skirt,) through which loops the hoops or springs are run, and are thus held on the tapes at the intended distance apart, but the tapes are not restrained thereby from moving to right or left on the hoops, another fastening being requisite to prevent such movement. It is immaterial what kind of tape is used, whether double or single, so long as the same is provided with a loop or pocket, or an equivalent therefor, on one side, through which the hoops or springs are to pass for holding them at a proper distance apart.

In Figure 5, I have shown a fastening well adapted for carrying out my invention. It is a semi-tubular piece of metal, B, provided with projecting lips, $b b'$, at each end of which lips are folded down over the hoop on each side of the pocket, the hoop and pocket being supported, as it were, in the groove, as will be understood by reference to the drawing.

The work of fastening the hoops or springs to the tapes can be performed by the same operative who runs the hoops through the pockets, and while the skirt is yet upon the frame, thus saving in handling the skirts as now practised, and hence in labor and expense.

It will be observed by my improved mode of securing the hoops or springs to the tapes in the manufacture of hoop-skirts—

First, that the metallic fastening is clasped around the hoop or springs, not through or to the tape, as is usual.

Second, that the "shirr" or loop is confined to the hoop, the main portion of the tape being free from the hoop, except as connected by means of the loop; thus the "bagging" of the tape is, in a great measure, prevented, and an easier bodily movement of the hoops secured.

Third, that when the tape, as in most cases it would be, is made wider than the pocket, the whole metallic fastening is entirely concealed behind the tape, and hence a skirt of a neater and more attractive appearance is obtained.

Fourth, that the fastening is more secure than those now usually employed, and that it is, as a whole, more desirable, neater, easily applied, and secure than those now employed, and that there is no liability, with such mode of fastening, of the hoop being freed from the tape by reason of the metallic fastening unclasping, and no liability of points projecting to tear the ladies' clothes.

It is evident that two tapes could be used and stitched

together to form pockets, and in order to obtain all the advantages of my invention, the inner tape could be narrower than the outer one.

I am aware that a clasp is used which crosses the tape on the outside, and whose points are turned down on the hoop at each side of the tape, but in such cases the device is provided with other points, intermediate of its length, which pass through the tape, to properly effect the securing together of the tape and hoop, which tape is seldom, if ever, provided with pockets or loops. It is evident that this does not meet my invention.

What I claim as my invention, and desire to secure by Letters Patent, is—

The combination, with the hoop or wire and the tape of a hoop-skirt, when said tape is provided with a pocket or loop of lesser width than such tape, of a metallic clasp or fastening, of such length that when its lips are clasped around said hoop or wire, it will not be practically visible when looking at the face or outside of the tape, the whole arranged and operating substantially as and for the purposes herein specified.

FRANCIS E. DAY.
